UNITED STATES PATENT OFFICE.

JOHN J. HALLIWELL, DECEASED, LATE OF TUCKAHOE, NEW YORK; BY MARGARET A. HALLIWELL, EXECUTRIX, OF TUCKAHOE, NEW YORK, ASSIGNOR TO R. HOE & CO., INC., OF NEW YORK, N. Y., A CORPORATION OF NEW YORK.

FOLDING MECHANISM.

Application filed January 25, 1928. Serial No. 249,469.

This invention relates to certain improvements in rotary folding mechanisms.

In certain folding mechanism, particularly rotary folders, the product is taken on the cylinder by suitable sheet taking devices and advanced by the cylinder to a pair of rolls, into which it is tucked by a folding blade, these rolls acting to fold off the product from the cylinder. In such mechanisms a variation in the speed of the cylinder causes an irregularity in the fold produced in successive products. As, for instance, when the cylinder is starting its rotation or running at slow speed, the leading end of the sheet, that is, the end taken by the sheet taking devices, is not advanced past the folding rolls by the sheet taking devices quite far enough, with the result that when the tucking blade acts to fold the sheet the tail end of the sheet will lap over the head end, thus producing an irregular fold. On the other hand, if the cylinder is being driven at high speed, the throw of the cylinder is apt to cause the sheet to be advanced too far before it is folded, with the result that the head end of the sheet laps over on the tail end, thus producing an irregular fold.

It is the object of the present invention to provide a rotary folding mechanism in which the point of operation of the folding blade may be adjusted with relation to the rotation of the cylinder to compensate for the tendency of the sheet to pass too far beyond the blade when the speed of the press is increased, so that with proper adjustment the product will always be folded exactly in the centre.

A further object of the present invention is to provide a means for supporting the folding rolls so that they will partake of the movement of the adjusting mechanism for the folding blade and so that they will always be in correct position with relation to the folding blade.

A further object of the invention is to provide an improved construction whereby the means for effecting the adjustment of the blade and for adjusting the folding rolls with respect to each other may be operated while the press is running.

A further object of the invention is to produce a simple and compact arrangement of the parts for effecting the desired function which

are readily accessible for replacement or repair.

With these and other objects not specifically referred to in view, the invention consists in certain novel parts, arrangements and combinations which will be described in connection with the accompanying drawings and the novel features pointed out in the claims hereunto annexed.

In the drawings,—

Figure 1 is an end view of a folding cylinder, partly sectional and partly broken away, the view being taken on Line 1—1 of Figure 2 looking in the direction of the arrow;

Figure 2 is a plan view, partly in section with certain parts being omitted, of the mechanism shown in Figure 1 on the irregular line 2—2 of that figure, and

Figure 3 is a side view of the mechanism shown in Figure 1, the view being taken in the direction of arrow 3 of that figure.

Referring now to these drawings, the invention has been illustrated as employed in connection with mechanism in which sheets are cut from a web and folded. It will be understood, however, that the invention is applicable for folding cut sheets supplied from any suitable source.

In the specific machine illustrated, 1 indicates suitable side frames for supporting the parts of the mechanism hereinafter referred to. In the construction illustrated a web W, which is forwarded by the usual forwarding rolls 2, 3, has sheets cut therefrom by suitable cutting mechanism, which is shown as a cutting cylinder 4 provided with a cutting knife 5, this cylinder cooperating with a cylinder 6, which is provided with the usual cutting woods 7. The cylinder 4, however, is half the diameter of the cylinder 6 and a sheet is cut from the web at each revolution of the cylinder 4 and each half revolution of the cylinder 6.

The cylinder 6 is a rotary folding cylinder and is provided with sheet taking devices in the form of pins 8, one set of which is shown, and with rotary tucking blades 9 which cooperate with a pair of folding off rolls 10, 11, between which the product is tucked by the tucking blades 9, and which act to produce a transverse fold in the product.

In accordance with the invention, means are

provided for operating this tucking blade and for effecting a relative movement between the tucking blade and its operating mechanism, so that the point at which the blade operates 5 to tuck a sheet into the rolls may be varied with respect to the rotation of the cylinder, it being understood that the sheet is always cut at the same point on the cylinder.

After the sheet is cut from the web and 10 the pins 8 have been withdrawn, it is free until the folding blade 9 presses it against the folding roller 11. The distance the sheet will travel during the period it is free is governed by its momentum which in turn is 15 governed by the speed of the press. When the press is running at slow speed the sheet will have little momentum and will be stopped when the folding blade comes in contact with it, but when the press is running at high 20 speed the sheet will slide over the edge of the folding blade to some extent and cause the fold to be made nearer the trailing edge of the sheet. The adjusting movement of the blade with respect to the rotation of the cylinder provides means to compensate for the 25 variation in the slip of the sheet at different press speeds and for adjustment so the fold may be made accurately in the centre of the sheet under all conditions. Furthermore, in 30 accordance with the invention, means are provided whereby the folding rolls may partake of this adjusting movement, so that no matter what this adjusting movement may be the folding rolls will always be in correct 35 relation to the folding blade.

In the particular construction illustrated there is provided a pair of annular members or rings 12, 13, which have an adjusting movement in arcuate guide members 14, 15 40 secured to the side frames 1 by bolts 16, as best shown in Figure 2. The member 12 is provided with an internal gears 17 which engages a gear 18 by which the folding blade 9 is operated. It will be observed that by 45 shifting the position of the gear 17 the position of the gear 18 will also be shifted and the point at which the tucking blade engages the rolls will be varied with respect to a sheet length cut by the cutting mechanism. While 50 this adjustment may be of various characters, in the particular construction shown the guide member 14 is provided with pins 19, which project through slots 20 (see Figure 55 1) in the gear ring 12 and act to guide this gear ring when it is moved to effect an adjusting movement of the folder blade.

Various constructions may be employed 60 for effecting a shifting movement of the gear- 65 ing 12. In the best constructions, however, for purposes hereinafter referred to, these means will also effect a similar shifting movement of the ring 13. In the specific construction illustrated the ring 12 is provided with a bracket 21, suitably secured thereto by bolts 22, and carrying a swivel nut 23 which re-

ceives the threaded end of a vertical adjusting rod 24. The lower end of this rod has a bearing in a bracket 24' secured to frame 1 and carries a hub 25 to which is secured a mitre gear 26 which meshes with a mitre gear 27 on a cross shaft 28, this shaft, outside the frame, being provided with a hand-wheel 29, by which it may be operated. Similarly, the ring 13 is provided with a bracket 30 carrying a swivel nut 31 through which extends a vertical rod 32, which at its lower end has a bearing in bracket 32' and carries a mitre gear 33 which meshes with a mitre gear 34 on the shaft 28.

It will be observed that by turning the 80 hand-wheel 29 in the desired direction the gear ring 12 will be given a slight rotary movement and will thus effect an adjustment in the position of the folding blade. Furthermore, it will be noted that this movement 85 of the rings 12, 13 may be effected while the machine is operating, so that when the speed of the press is changed the folding blade may be shifted to the desired point for effecting the correct folding of the product. Cooperating with the folding blade are the folding rolls 10, 11 before referred to. In accordance with the invention, these folding rolls are supported so that they will partake of the 90 adjusting movement of the operating rings 95 12, 13, before referred to, these rolls moving with the rings, so that the rolls are always positioned in correct relation with the folding blade.

While the particular means for effecting 100 this may be varied within wide limits, in the particular construction illustrated the gear ring 12 is provided with brackets 35, 36, suitably secured to the ring by bolts 37. In these brackets are mounted the usual spring supports 38, 39, which carry hubs 40, 41 in which one end of shafts 42, 43 of the rolls are mounted. The other end of the shafts 42, 43 of the rolls are mounted in similar hubs 44, 45 carried in supports 46, 47 supported by brackets 105 48, 49 bolted at 50 to the ring 13. The spring supports permit the folding rolls 10, 11 to separate, if necessary, to provide for the folding off of products of different thicknesses. With this construction it will be observed that 110 as the rings 12, 13 are moved by the shaft 28 the folding rolls partake of this movement, so that they in effect follow the folding blade and are always in proper position with respect to the folding blade to form a fold in the product 115 on its center line. Thus a simple and effective mechanism for preventing under or over folding has been provided.

Means are provided for driving these folding rolls and in the best constructions these 120 means will be such that the rolls may be spread apart to provide for the folding off of products of different thicknesses without effecting the meshing of the gears by which they are driven. While these means may be varied 125 130

within wide limits, the preferred one is that illustrated. The specific structure disclosed for effecting this is provided with a depending portion 51 extending below its circumference, 5 in which are supported the gears by which the folding rolls are driven, these gears being located outside the frame, as shown in Figures 2 and 3. As shown, there is provided a large gear 52 (see Figure 1) which is fast on shaft 10 53 of the folding cylinder 6. This gear meshes with a gear 54 supported on a stud 55 which drives an idler gear 56 which in turn meshes with an idler 57. The gear 57 is fast on a shaft 58 to which is also secured a gear 59 which meshes with a gear 60 on the left-hand folding roll 10 (see Figure 1). Likewise, the gear 56 is fast on a shaft 61, on which is also secured a gear 62 which meshes with a gear 63 on the shaft of the right-hand folding roll 11. 20 In the best constructions, means are provided for effecting a separating movement of the folding rolls 10, 11, these means being such that it may be done while the machine is running and so that the same adjusting movement is given both ends of the rolls, so that 25 the rolls will remain in parallelism. In the particular construction illustrated, the spring supports 38, 39 and 46, 47 move in ways 64 in their supporting brackets, and are simultaneously adjusted toward or away from each other by means of a screw rod 65 having right and left-hand threads. This screw rod 65 is provided at one end with a mitre gear 66 which meshes with a mitre gear 67 on a cross 30 shaft 68, this cross shaft at its end beyond the frame being provided with a hand-wheel 69, by which the shaft may be manipulated. Similarly, the supports 46, 47 are adjusted toward and from each other and to the same extent as the supports 38, 39. As shown, this is effected by a screw rod 70 having right and left-hand threads, this screw rod at one end being provided with a mitre gear 71 which 35 meshes with a mitre gear 72 on the shaft 68. 40 Both the shafts 28 and the shafts 68 may be locked in adjusted position by means of locking collars 73, 74.

With the construction shown and described and with the understanding that the sheet is severed at a fixed point during the revolution of the folding cylinder, it will be observed that the folding blade can be adjusted as desired while the machine is running to produce a centre fold. Thus when the press is running slowly the folding blade may be timed to engage the folding rolls at a certain position relatively to the sheet length. During the rotation of the cylinder, the position of the blade can be shifted as the speed of the press is increased, and this can be done while the machine is running, so that the folding blade and the cooperating folding rolls always act to produce a centre fold in the product.

While the invention has been described and

shown in its preferred form, it will be understood that various changes and modifications may be made in the particular mechanisms selected as illustrative of the invention and that the invention is not to be restricted to the precise mechanisms shown and described.

What is claimed is:

1. In a folding mechanism, the combination of a folding cylinder having a tucking blade, means for operating the blade, and folding rolls cooperating with the blade and supported by the blade operating means.

2. In a folding mechanism, the combination of a folding cylinder having a tucking blade, means for operating the blade, means for effecting a relative adjusting movement of the blade and the operating means, and folding rolls supported to partake of the adjusting movement.

3. In a folding mechanism, the combination of a folding cylinder having a tucking blade, a gear for operating the blade, a cooperating gear, means for adjusting the position of the latter gear, and folding rolls mounted to move with the latter gear.

4. In a folding mechanism, the combination of a folding cylinder having a tucking blade, a gear for operating the blade, a co-operating gear, a rotary member, a pair of folding rolls supported by the latter gear and member, and means for simultaneously moving the latter gear and member for adjusting the position of the tucking blade and the rolls.

5. In a folding mechanism, the combination of a folding cylinder having a tucking blade, means for operating the blade, means operable while the machine is running for effecting a relative adjusting movement of the blade and the operating means, and folding rolls supported to partake of the adjusting movement.

6. In a folding mechanism, the combination of a folding cylinder having a tucking blade, a gear for operating the blade, a co-operating gear, means operable while the machine is running for effecting an adjustment of the latter gear, and folding rolls mounted to move with the latter gear.

7. In a folding mechanism, the combination of a folding cylinder having a tucking blade, means for operating the blade, means operable while the machine is running for effecting an adjusting movement of the operating means, a pair of folding rolls mounted to partake of the adjusting movement, and means operable while the machine is running for effecting a movement of the rolls toward and from each other.

8. In a folding mechanism, the combination of a folding cylinder having a tucking blade, means for forwarding a web, means for cutting sheets from the web at a fixed point, means for operating the blade, means for ef-

fecting an adjusting movement of the blade operating means to adjust the position of the blade with respect to the sheet, and folding rolls supported to partake of the adjusting movement.

9. In a folding mechanism, the combination of a folding cylinder having a tucking blade, means for forwarding a web, means for cutting sheets from the web at a fixed point, means for operating the blade, means operable while the machine is running for effecting an adjusting movement of the blade operating means to adjust the position of the blade with respect to the sheet, and folding rolls supported to partake of the adjusting movement.

10. In a folding mechanism, the combination of a folding cylinder, a tucking blade, a gear for operating the blade, a cooperating ring gear, means for adjusting the position of the ring gear, a ring opposite the ring gear, means for adjusting the ring, and folding rolls supported by the ring gear and ring.

11. In a folding mechanism, the combination of a folding cylinder, a tucking blade, a gear for operating the blade, a cooperating ring gear, an adjusting rod connected with the gear, a shaft for operating the rod, a ring opposite the ring gear, means for adjusting the ring, and a pair of folding rolls supported by the ring gear and ring.

12. In a folding mechanism, the combination of a folding cylinder, a tucking blade, a gear for operating the blade, a cooperating ring gear, a ring opposite the ring gear, folding rolls supported by the ring gear and ring, a shaft, and connections from the shaft for

simultaneously adjusting the ring gear and ring.

13. In a folding mechanism, the combination of a folding cylinder, a tucking blade, a gear for operating the tucking blade, a co-operating ring gear, a pair of folding rolls, journals for one end of the rolls carried by the brackets, a ring opposite the ring gear, brackets carried by the ring, journals for the other end of the rolls carried by the ring brackets, and means for adjusting the position of the ring gear and ring.

14. In a folding mechanism, the combination of a folding cylinder, a tucking blade, a gear for operating the tucking blade, a co-operating ring gear, brackets carried by the ring gear, a pair of folding rolls, journals for one end of the rolls carried by the brackets, a ring, brackets carried by the ring, journals for the other end of the rolls carried by the ring brackets, rods connected to the ring gear and ring, and a shaft for operating the rods.

15. In a folding mechanism, the combination of a folding cylinder, a tucking blade, a gear for operating the blade, a cooperating ring gear, folding rolls supported at one end by the ring gear, means for supporting the other end of the rolls, means for adjusting the position of the ring gear, and means supported from the ring gear for adjusting the rolls toward and from each other.

In witness whereof I have hereunto signed my name.

MARGARET A. HALLIWELL,
*Executrix of the Estate of John J. Halliwell,
Deceased.*
